(57) **CLAIM**

The ornamental design for a bank note sorting and counting machine component, as shown and described.

DESCRIPTION

FIG. 1 is a perspective view of a bank note sorting and counting machine component according to our new ornamental design;

FIG. 2 is a front view thereof;

FIG. 3 is a left side view thereof; and,

FIG. 4 is a top plan view thereof.

The broken lines showing environment or structure are for illustrative purposes only and form no part of the claimed design.

The bottom, right, and rear sides of the bank note sorting and counting machine component, not pictured, do not form any part of the claimed design.
